EXTENSIONS

UNITED STATES PATENT OFFICE.

CHARLES MARKEL, OF CLINTON, IOWA.

CROSS-HEAD.

1,202,866.

Specification of Letters Patent. Patented Oct. 31, 1916.

Application filed June 18, 1915. Serial No. 34,793.

To all whom it may concern:

Be it known that I, CHARLES MARKEL, a citizen of the United States, residing at Clinton, in the county of Clinton and State of Iowa, have invented certain new and useful Improvements in Cross-Heads, of which the following is a specification.

This invention relates to locomotive cross heads and their slippers and it has for one of its primary objects the provision of a novel cross head and slipper device in which the slippers are firmly and securely held in place, while at the same time the slippers may be removed without disturbing the guides. Another of the primary objects of my invention is the provision of novel means for securing the slippers to the cross head so that the slippers will remain tight, such means being so arranged that the bolts which are utilized in fastening the slippers to the cross head are placed under no shearing stresses. My invention also contemplates the provision of a novel form of slipper and cross head, so constructed that the expense of manufacture is greatly reduced and assembling simplified and shortened.

The foregoing, together with such other objects as may hereinafter appear or are incident to my invention I attain by means of a construction which I have illustrated in preferred form in the accompanying drawings wherein:

Figure 1 is a partial side elevation and section of my improved form of cross head and cross head slippers; Fig. 2 is an end elevation and partial section of the device of Fig. 1; Fig. 3 is a plan view of the cross head with the slipper removed, such figure being drawn on a small scale; and Fig. 4 is a side elevation on a small scale of one of the slippers.

A locomotive cross head forms the pivotal connection between the piston rod and the adjacent end of the pitman, and it reciprocates between guides located immediately to the rear of the cylinders, the chief function of the cross head being to relieve the piston rod of lateral stresses from the pitman or crank rod. The slippers carry the lining plates or bearing brasses and fit the guideways and are in turn carried on the cross head. When the bearing brasses become worn and they or the slippers require renewal, the slippers must be removed and it is old in this art to detachably mount

the slippers on the cross head so that the slippers can be removed without disturbing the cross head. As previously pointed out, this invention has primarily to do with the construction, arrangement and fastening means of the cross head and slippers whereby the slippers are securely maintained in place.

In the general type of cross head and cross head slipper, just described, it has been customary to secure the slippers to the cross heads by six or eight fit bolts, three or four to hold the top slipper to the cross head, and the same number to hold the bottom slipper. The holes to receive the slipper bolts have to be reamed and tapered and the bolts themselves must be machine-turned bolts in order to hold the slippers to straight fits in the openings in the cross head. Cross heads in the course of a short time wear loose between the guides which results in a pounding received on the slippers and transmitted by the slippers to the fit bolts, the result of which is that the bolts receive all of the stresses and become worn and wear the holes or openings in the cross heads larger. One of the chief defects which marks this form of construction is that no amount of tightening on the nuts of the slipper bolts will prevent the slippers from working or shifting on the cross heads, and it is necessary to take down the entire cross head, re-ream the bolt holes and apply new bolts. This must be done several times during the course of a year and in several years the holes in the cross heads and the slippers become so enlarged that they are unsafe and useless and must be scrapped or plugged and welded and re-drilled. Furthermore because of the constant looseness of the slippers, the fits become so worn that it is impossible to maintain a standard for purposes of duplication.

My invention is designed to overcome these difficulties and also those which are present in that type of cross head devices in which the slippers are made adjustable, this latter form presenting certain structural difficulties which render it impractical.

Referring now to the drawings, the cross head proper is indicated by the numeral 7. In the upper and in the lower face of the cross head is a slot or opening 8 to receive a slipper, said slot or slipper opening being open at the rear end to permit the insertion of the slipper. The two side walls of the

slipper openings are undercut, tapered or beveled as indicated at 9 in Fig. 2, the dimensions of the opening decreasing toward the respective face of the cross head; and the end wall is also undercut or beveled as indicated at 10 in Fig. 1. The face of the side and end walls are machined to provide an extended seat 20 for the slippers. The bolt hole 11 extends through the side walls 10 of each slipper opening toward the rear end thereof and transversely of the cross head, as shown in Figs. 2 and 3; and a bolt hole 12 extends through the end wall of each slipper opening longitudinally of the cross head.

The slippers are indicated by the numeral 13 and each is provided with a bearing brass 14 formed to fit the guides. Projecting from the inner face of each slipper is a shoulder 20 comprising two side walls and an end wall, the outer faces of which are undercut, tapered or beveled inversely with respect to the bevel of the corresponding portions of the slipper openings. This construction of 25 the slipper is shown in Figs. 1, 2 and 4, from inspection of which it will be seen that the slippers are slipped into position through the open end of the slipper openings in a dove-tail engagement with the cross head. 30 Toward the rear end of each slipper there are cored openings or slots 15 which correspond to and align with the bolt holes 11 in the side walls of the slipper openings and clear the bolt one-eighth of an inch all 35 around. At the forward end there is a bolt hole 16 in the slipper corresponding to and aligning with the bolt hole 12 in the cross head. All of these bolt holes and slots do not have to be reamed. 40 Each slipper is held in place by two rough bolts, a bolt 17 passing through the bolt holes 11 and slots 15, and a bolt 18 passing through the bolt holes 12 in the cross head and 16 in the slipper. The bolts have 45 the usual nuts 19 and nut locks 20^a of any preferred construction.

When the nuts 19 are tightened on the bolts 17, the side walls of the slipper openings are pinched or sprung inwardly, drawing 50 the beveled faces into tight engagement with the beveled faces of the slipper shoulders, and because of the incline or taper of these faces, the slippers are drawn into tight engagement with the extended seat 20 of the 55 slipper opening walls. It will be understood of course that those portions of the slippers which rest on the surface 20 are also machined. When the nuts 19 of the bolts 18 are tightened, it brings the beveled surfaces 60 at 10 together and draws the slipper into contact with the seat 20. In assemblage, however, the bolts 18 are first tightened to properly position the slipper with respect to the cross head. From the foregoing it will 65 be seen that an extended bearing surface for

the slippers is provided not only by the seat 20 but also by the contacting beveled faces which are co-extensive with the walls of the slipper openings. The advantage of such an extended bearing surface or seat between the 70 cross head and the slippers is that the liability of wear is reduced to a minimum, if not made practically negligible. Furthermore in the event that the slippers become loose, they can be tightened merely by turning up the nuts 19. It will be apparent 75 from the foregoing that the construction is simple, that the bolts are relieved of shearing stresses, that a superior bearing is provided for the slippers on the cross head, 80 and that the device is inexpensive, this latter advantage resulting from the fact that it is not necessary to ream the bolt holes nor to use machine turned bolts; nor to replace the bolts or reream the bolt holes when 85 tightening a loose slipper. In addition, the number of bolts required is reduced, and it is likewise possible to standardize the parts so that in the event of breakage, a new slipper or new bolts may be substituted. Rough 90 bolts can be readily replaced because the bolt holes are considerably larger than the bolts. By providing beveled faces at both the sides and the forward end of the slipper openings and slippers, the slippers are held against 95 both longitudinal and lateral displacement and the area of the contacting faces is greatly increased, with a consequent increase in resistance to longitudinal movement of the slippers. While the slippers are rigidly 100 clamped in position, and the liability of their pounding loose is reduced to a minimum, yet they can be readily detached when it is found necessary to refine or replace a slipper. Other advantages will occur to 105 those skilled in the art.

I claim:—

1. A cross head device comprising in combination a cross head having a slipper-receiving recess the side and end walls of 110 which are beveled, a slipper having an oppositely beveled portion adapted to be slipped into said recess, a transversely-extending clamping element and a longitudinally extending clamping element adapted to clamp 115 said beveled portions together transversely and longitudinally of the cross head whereby to draw the slipper into engagement with the cross head.

2. A cross head device comprising in combination a cross head having an under-cut slipper-receiving groove open at one end and closed at the other, a slipper having an oppositely under-cut shoulder fitting said groove and having a bolt-receiving opening, 120 a bolt passing transversely through the cross head and said shoulder to clamp the side walls of the groove against said shoulder, and a bolt passing longitudinally through 125 the end wall of the groove and into the bolt- 130

receiving opening to clamp said end wall against the shoulder.

3. A cross head device comprising in combination a cross head having a seat, a slipper adapted to take against said seat, the cross head and slipper having oppositely formed coacting sloping portions substantially co-extensive with the slipper in length and arranged when clamped together substantially transversely to slide upon each other and draw the slipper toward the cross head against its seat, and means for clamping said portions together substantially transversely.

15 4. A cross head device comprising in combination a cross head having a seat, a slipper adapted to take against said seat, the cross head and slipper having oppositely formed coacting sloping portions arranged when clamped together substantially transversely to slide upon each other and draw the slipper toward the cross head against its seat, and means for clamping said portions together substantially transversely, said 20 means extending through both cross head and slipper and having a lost motion connection with one of them.

5. A cross head device comprising in combination a cross head and a slipper, each having an oppositely formed coacting beveled portion arranged when clamped together substantially transversely to slip upon each other and draw the slipper toward the cross head, and means for clamping said beveled portions together substantially transversely.

30 6. A cross head device comprising in combination a cross head and a slipper, each having an oppositely formed coacting

beveled portion arranged when clamped together substantially transversely to slip upon each other and draw the slipper toward the cross head, and means for clamping said beveled portions together substantially transversely, the frictional engagement of said coacting portions preventing relative longitudinal movement of the cross head and slipper thereby relieving the clamping means of shearing stresses.

7. A cross head device comprising in combination a reciprocating cross head having an undercut portion and an abutment surface, a slipper having an oppositely undercut portion coacting with the undercut portion of the cross head and adapted to take against said abutment surface, and means for clamping said portions together substantially transversely, the said undercut portions being arranged to draw the slipper against said abutment surface when clamped together substantially transversely and being adapted to prevent relative shifting of the cross head and slipper, thereby relieving the clamping means of shearing stresses.

8. In a reciprocating cross head device, the combination of a cross head having a seat, a slipper adapted to take against said seat and a compound means for drawing said slipper against its seat, said means comprising reversely formed coacting portions on the cross head and slipper, together with a clamping means adapted to clamp said portions together, the frictional engagement of said portions relieving the clamping means of shearing stresses.

In testimony whereof I have hereunto signed my name.

CHARLES MARKEL.
